RUNNING BOARD SADDLE

James S. Swann, Homewood, Ill., assignor to
Standard Railway Equipment Manufacturing
Company, Chicago, Ill., a corporation of Delaware

Application December 5, 1951, Serial No. 260,065

6 Claims. (Cl. 105—457)

1

This invention relates to improvements in railway freight car running boards of the bar type which comprise sets of interconnected longitudinal and transverse bars disposed vertically edgewise and having serrated type portions such, for example, as illustrated in Patent No. 2,203,020 dated July 16, 1940.

More specifically, the invention comprises an improved saddle for bar type running boards, which saddles are in turn secured to the seam caps of the car roof. Most car roofs now comprise roof sheets extending from side to side of the car and provided with upstanding marginal flanges which are straddled by a carline or seam cap through which rivets extend for securing the flanges and seam cap together, thereby providing a watertight joint.

The principal object of the invention is to provide a running board saddle for bar type running boards which requires no additional hold-down parts, such as bolts or rivets, thereby reducing the application cost of the running board to a car roof.

Other objects and advantages of the invention will become apparent from the following description thereof.

Referring now to the accompanying drawing forming part of this application and wherein like reference characters indicate like parts.

Fig. 1 is a perspective view of a bar type running board showing my improved saddle applied thereto and supporting the same upon a car roof.

Fig. 2 is a perspective view of the running board.

Fig. 3 is a view similar to Fig. 1 showing a modified form of saddle.

Fig. 4 is a perspective view of the saddle shown in Fig. 3.

In the drawings a portion of adjacent car roof sheets is shown at 10, the adjacent margins of which are provided with upstanding flanges 11 which abut each other and are straddled by a carline seam cap 12. Rivets 13 extend through the seam cap and flanges to form a watertight joint between the adjacent roof sheets.

The running board saddle comprises an angle shaped piece of metal comprising flanges 14 and 15, and the saddle is of a length to extend from side to side of the running board. The bottom edge of the flange 14 conforms to the plane of the roof, sloping downwardly from the approximate center thereof to the opposite ends. When on the car this flange is disposed vertically and provided with spaced holes 16, which holes are

5 the same distance apart as the holes accommodating the rivets 13, so that some of these rivets may also hold the saddle to the seam cap. The flange 15 is horizontally disposed and straight to support thereupon the bottom edges of the longitudinally extending bars 17 of the running board. The running board comprises a plurality of these longitudinally extending bars 17, which are disposed on edge and are held together in spaced 10 relation by spaced transverse bars secured to bars 17 by deformation. Adjacent the opposite ends of this flange 15 are die-cut upwardly from the flange, wedge shaped lugs 18, which are then bent intermediate their ends so that the tip portion extends substantially parallel to the remainder of flange 15. Spaced inwardly from these lugs 18 a suitable distance are also die-cut 15 upwardly a pair of vertically extending rectangularly shaped lugs 19. The lugs 18 are spaced 20 so that they occur adjacent the inner faces of the outer longitudinal bars 17 of the running board (which outer bars are provided with longitudinally extending slits 20) when the running board is applied to the saddle. Then with a hammer the wedge shaped lugs 18 are forced through 25 said slits 20 and the end protruding through said slits bent over to clamp the running board in place. The other vertical lugs are positioned so that the outer edges thereof occur in abutting 30 relation with the inner face of an intermediate longitudinal running board bar 17 and the vertical edges of said lugs 19 may be welded to the said side of said bars 17. These lugs 19 eliminate lateral movement of the running board and strain from the lugs 18, and it is not absolutely 35 necessary that they be welded to the adjacent running board bars 17 since the lugs 18 securely hold the entire running board in place.

A modification of the running board saddle is shown in Figs. 3 and 4, wherein the saddle comprises an angle member comprising flanges 25 and 26. Flange 25 is similar to flange 14 except that end extensions 27 are provided which are of sufficient length that two rivets 13 also extend through holes 28 to hold the saddle to the seam cap. Embossments 29 are pressed outwardly in this flange 25 so as to overlap the intervening rivet heads 13 in the seam cap. The other flange 26 has die-cut therefrom a pair of angularly shaped lugs 30 which are of a width to span the space between two adjacent longitudinal bars 31, so that the side edges of said lugs may be welded, as at 32, to the adjacent sides of a pair of said longitudinal bars 31 to hold the running board securely in place. Since the welds 32 run

in a diagonal as well as a longitudinal direction such fastening eliminates the possibility of movement of the running board in any direction.

Having thus described my invention, what I claim and desire to secure by Letters Patent, is:

1. A running board saddle adapted to support a preassembled unit bar type running board to a car roof, comprising an angular bracket member having flanges extending in planes at right angles to each other, and means to secure one of said flanges to a car roof, the other flange having outwardly pressed lugs spaced so as to occur in edge relation to the sides of longitudinal bars of a bar type running board to secure said running board to said saddle.

2. A running board saddle adapted to support a preassembled unit bar type running board to a car roof comprising an angular bracket member having flanges extending in planes at right angles to each other, one of said flanges having spaced holes therethrough for fastening means to secure said saddle to a car roof, the other flange having outwardly pressed lugs engageable with the sides of longitudinal bars of a bar type running board to secure said running board to said saddle.

3. A running board saddle adapted to support a preassembled unit bar type running board to a car roof comprising an angular bracket member having flanges extending in planes at right angles to each other, one of said flanges having outwardly pressed lugs spaced so as to occur in edge relation to the sides of longitudinal bars of a bar type running board to secure said running board against lateral displacement.

4. A running board saddle adapted to support a preassembled unit bar type running board to a car roof comprising an angular bracket member having flanges extending in planes at right angles

5

to each other, one of said flanges having spaced holes therethrough for fastening means to secure said saddle to a car roof, the other flange having outwardly pressed lugs spaced so as to occur in edge relation to the sides of longitudinal bars of a bar type running board to secure said running board against lateral displacement on a car roof.

5. A running board saddle adapted to support a preassembled unit bar type running board to a car roof, the outer bars having slits therethrough comprising an angular bracket member having flanges extending in planes at right angles to each other, and means to secure one of said flanges to a car roof, the other flange having outwardly pressed lugs deformable to extend through said slits to secure said running board to said saddle.

6. A running board saddle adapted to support a preassembled unit bar type running board to a car roof, the outer bars having slits therethrough comprising a bracket member having flanges extending in planes at right angles to each other, means to secure one of said flanges to a car roof, the other flange having outwardly pressed lugs deformable to extend through said slits and thereby hold said running board to said saddle, and other lugs pressed outwardly from said other flange engageable edgewise with the sides of other bars of said running board.
